United States Patent Office.

D. FRANK HALE, OF CHICOPEE, MASSACHUSETTS.

Letters Patent No. 102,538, dated May 3, 1870.

IMPROVEMENT IN REVERSIBLE BUTT-HINGES.

The Schedule referred to in these Letters Patent and making part of the same.

I, D. FRANK HALE, of Chicopee, in the county of Hampden and State of Massachusetts, have made and invented a new and useful Improvement in Reversible Butt-Hinges, of which the following is a specification, reference being had to the accompanying drawings making a part of the same, wherein—

Figure 1 is a side elevation of a hinge embodying my invention;

Figure 2, an end elevation of the same;

Figure 3, a side elevation, showing the barrel-cap removed; and

Figure 4, an end elevation of the same.

My invention consists in connecting the upper or projecting end of pintle *d* with leaf *e*, the object thereof being to strengthen the hinge and prevent the pintle being sprung or twisted from its proper position by any sudden strain or jar, and this I do by means of cap *a*, projection *b*, and slot *c*, and obviously the same result would be attained by means of a hole formed in the upper end of leaf *e*, and an elbow-hook projecting from the side of cap *a*.

The parts marked *e* and *f* represent the leaves, one of which, *e*, projects centrally from the barrel *i*, while the other, *f*, projects tangentially therefrom.

The pintle *d* is made fast in that part of the barrel

formed on leaf *e*, and of such length as to project upward nearly or quite to the top of such leaves. In the barrel edge of leaf *e*, I form a dovetail slot, *c*. I provide what I term the barrel-cap *a*, being really a portion of the barrel, on the side of which cap is formed a dovetail projection, *b*. Projection *b* slides into slot *c*, while pintle *d* enters a central hole in cap *a*, thus giving to a loose-joint reversible hinge the appearance, and to a considerable degree the strength, of a tight-joint hinge.

I am aware that a reversible hinge, with a barrel-cap similar to that herein described, has heretofore been made, and I do not claim the invention of such cap, but limit myself to the connection of the leaf and pintle, in the manner specified.

Claim.

What I claim as my invention is—
Connecting the upper or projecting end of pintle *d* and leaf *e*, by means of cap *a*, projection *b*, and slot *c*, substantially as specified.

D. FRANK HALE.
